VENTILATING WINDOW

Clarence E. Rickel, Toledo, Ohio, assignor to
Automobile Ventilation, Inc., Detroit, Mich., a
corporation of Michigan

Application March 22, 1935, Serial No. 12,394

10 Claims. (Cl. 268—126)

This invention relates to window regulator mechanism particularly adapted for use in vehicle bodies or the like for raising and lowering the windows thereof. Although susceptible of various uses and adaptations the invention is herein illustrated, by way of example, as applied to a ventilating window of an automobile body wherein the window when fully elevated is movable in its plane or edgewise longitudinally of the vehicle into and out of position to provide a ventilating slot or opening at the forward upright edge of the glass.

An object of the invention is to provide a regulator mechanism of the type having oppositely swinging arms wherein means is provided for developing a differential frictional resistance between the arms and window whereby the window will be urged or moved longitudinally during the vertical travel thereof.

A further object of the invention is to provide a regulator mechanism for moving the window glass horizontally or longitudinally in its plane from fully closed position into position whereby a ventilating slot is produced at the forward edge of the glass and thence in a downward vertical direction, and wherein means such as springs of different characteristics are provided between the arms of the regulator and the window glass rail effective to produce sufficient differential friction to change the path of movement of the glass during its vertical travel.

Other objects of this invention will appear in the following description and appended claims, reference being had to the accompanying drawing forming a part of this specification wherein like reference characters designate corresponding parts in the several views.

For purposes of illustration, but not of limitation, an embodiment of the invention is shown in the accompanying drawing, in which:

Figure 1 is a side elevation of a portion of an automobile door viewed from the inside with the upholstery removed and showing the window in its closed position, dot and dash line showing the window moved rearwardly to provide a ventilating opening;

Figure 2 is an enlarged edge view of the upper end of the forward regulator arm showing the rail-engaging stud and spring pressed washer; and

Figure 3 is a view similar to Figure 2 showing the rear regulator arm, stud and spring pressed washer.

The illustrated embodiment of the invention 55 has the usual window opening 11 and window 12

guided in its vertical movements by front and rear runways 13 and 14 respectively. The runway 13 is relatively narrow, whereas runway 14 is relatively deep and extends from its upper end downwardly to a point below the window opening 11 where it inclines downwardly and forwardly, as indicated at 15. By providing the inclined portion 15 of the runway, ample clearance is afforded for the operating spindle 16 of the door latch (not shown), a handle 17 being disposed on the outside of the door and operatively connected to the outer end of the spindle 16 for actuation thereof. The lower portion of the runway 13 is made deeper, as indicated at 18, and inclines downwardly and forwardly similar to the runway portion 15.

Embracing the lower edge of the window 12 is a channel strip 19 of U-shape, and between the strip 19 and the window is disposed suitable packing. Fixed to one side of the channel strip 19 are rails 20, which are slotted to receive pins 21 and 22 carried by the outer ends of regulator arms 23 and 24 respectively. Secured to the lower end of the regulator arm 23 is a gear sector 25 meshing with a similar gear sector 26. Integral with the gear sector 26 and concentric therewith is a larger sector 27 with which a pinion 28 meshes. The pinion is operated by a suitable handle (not shown) disposed on the inside of the door, and these parts are carried by a mounting plate 29, on which pivot pins 30 and 31 for the sectors 25 and 26 respectively, are carried. A counterbalance spiral spring arrangement 33 is provided for the gear sectors, as will be readily understood by those skilled in this art, a suitable clutch 34 associated with the pinion being also provided to retain the parts in adjusted position.

Fixed to the upper end of the regulator arm 23 is a plate 35 having a downwardly inclined finger-like extension 36, which is provided with an upwardly and rearwardly curved surface 37, terminating in a notch 38. Secured to the rail 20 and projecting outwardly therefrom is a pin 38a engageable by the notch 38. The plate 35 inclines downwardly and rearwardly from the notch 38 to the arm 23, as indicated at 39.

As shown in Figure 2, washers 40 are mounted on the studs 21 and 22 between the headed end thereof and the respective regulator arms. Mounted on the stud 21 and arranged to bear against the washer is a coil spring 41, the inner end bearing against the plate 35. A coil spring 41a on the stud 22 bears against the respective washer 40 for urging the latter outwardly. It will be understood that the washers 40 bear against

the outer face of the rail 20 and exert friction thereagainst preventing rattling of the parts. In this instance and in accordance with this invention, it will be noted that the spring 41a is stronger than the spring 41. For example, the spring 41a may be four times stronger than the spring 41. The advantage of this arrangement will herein-after appear.

The operation of the above mechanism is as follows:

Assuming that the window is in its raised position with the ventilating slot closed, the operating handle is moved to actuate the pinion 28, which, through the gearing above described, moves the regulator arms 23 and 24 in opposite directions away from each other. The notched portion 38 of the plate 35 is in engagement with the pin 38a so that upon movement of the regulator arm 23 to the right, the window 12 is caused to move to the right or rearwardly of the vehicle so that the front vertical edge of the window is moved out of the channel 13 and the rear vertical edge is moved into the relatively deep channel 14, as indicated by the dot and dash lines A. This provides a slot V between the front vertical edge of the window and the window frame through which foul air, smoke, gases, etc. may be drawn from the inside of the vehicle when the latter is moving forwardly. The window 12 is guided in such horizontal movement by the pins 21 and 22 riding in the rail 20.

When the window 12 has nearly completed its horizontal or transverse movement due to the angularity of the regulator arm 23, the finger extension 33 is moved so that the notch 38 clears the pin 38a so that subsequent swinging movement of the arms 23 and 24 in opposite directions causes the window to move vertically downward.

The window 12 is moved downwardly by the arms 23 and 24 until the inclined runways 15 and 18 are reached, the surface 37 of the finger-like extension 36 preventing the window 12 from being moved forwardly during such downward movement, inasmuch as the pin 38a abuts the surface 37.

Since the washer 40 on the stud 22 has greater pressure imposed upon it by the coil spring 41a, during the downward movement of the window the arm 24 tends to force the lower edge of the window to the left or forwardly of the vehicle against the inclined runway 18. Thus, during the further downward movement of the window the latter is held against the forward runway 18 and is caused to follow the inclined path of such runway. Not only does such differential spring pressure function to impart the inclined movement to the window 12, but it also militates against clamping of the window during its vertical travel.

It is apparent that when the direction of movement of the regulator arms 23 and 24 is reversed for the purpose of raising the window, the greater friction imposed on the rail by the spring 41a serves to force the rear edge of the window 12 against the inclined runway 15, thereby causing it to traverse the inclined path of such runway, and, as above mentioned, eliminates the tendency of the window to become clamped or jammed during such travel. It will be apparent that during the vertical movement of the window the front vertical edge is spaced from the runway, but, upon further actuation of the regulator mechanism in window closing direction through the cooperation of the notched portion 38 and pin 38a,

the window is shifted forwardly to close the ventilating slot.

It will be apparent that the characteristic feature of the invention resides in the provision of differential friction developed between the outer ends of the regulator arms and the rail, which, in this instance, operates to cause the window to travel in an inclined path during its vertical movements, and eliminate the tendency of the window to cramp. It is to be understood that this invention is not restricted to the inclined vertical movement of the window, because it is of importance in cases where the window moves in a straight vertical path, particularly for the purpose of avoiding jamming or cramping of the window during the raising and lowering movements.

Changes in details of construction, arrangement and operation may be made without departing from the spirit of the invention, especially as defined in the appended claims.

I claim:

1. In a regulator mechanism for a window having a rail secured to the lower edge thereof, a pair of swinging arms slidably connected to the rail for raising and lowering the window, and spring means adjacent the outer ends of said arms for producing materially greater frictional resistance between one arm and the rail than between the other arm and the rail during swinging movement of the arms thereby to urge the window longitudinally in its plane during its raising and lowering movements.

2. In a regulator mechanism for a window glass having a rail secured to the lower edge thereof provided with longitudinal guideways, a pair of oppositely swinging arms having devices at their outer ends adapted to travel in said guideways for raising and lowering the glass, and differential spring means adjacent the outer ends of said arms for producing materially greater resistance to the travel of one of said devices than the other during the swinging movement of the arms thereby to shift the glass longitudinally in its plane during its raising and lowering movements.

3. A window regulator comprising a pair of oppositely swinging arms having devices at their outer ends adapted to be connected to a window, washers mounted on said devices, and a compression spring interposed between each washer and an arm, one of said springs having a strength of the order of twice the strength of the other spring.

4. In a vehicle body having a window frame provided with runways and a window mounted for vertical sliding movement therein, a window regulator having oppositely swinging arms slidably connected to the lower edge of the window, and springs of materially different characteristics adjacent the outer ends of said arms for producing differential frictional resistance between said arms and window whereby to urge said window longitudinally in its plane in one direction or the other toward one or the other of said runways during the vertical movement thereof.

5. In a vehicle body having a window mounted for vertical and longitudinal movements in its plane, regulator mechanism for raising and lowering the window and also for shifting the window longitudinally into and out of position when raised to provide a ventilating slot at one upright edge of the glass, and differential friction means between said mechanism and window for shifting the window longitudinally in its plane in one direction or the other during the vertical travel thereof.

6. In a regulator mechanism for a vehicle body window mounted to slide vertically and also longitudinally in its plane, comprising a pair of oppositely swinging arms for raising and lowering the window and also for moving the window longitudinally when in raised position to provide or close a ventilating slot at the forward edge of the window, and differential spring means adjacent the outer ends of said arms and between said arms and window for effecting a longitudinal movement of the window intermediate its raised and lowered positions.

7. In a regulator mechanism for a vehicle body window, a rail secured to the lower edge of the window, a pair of oppositely swinging arms having devices at their outer ends slidingly engaging said rail, one of said arms having means cooperable with said rail for shifting the window in its plane into or out of position when fully raised to provide a ventilating slot at one upright edge of the glass, and one of said arms having means cooperating with one of said devices for producing materially greater frictional resistance to its travel on the rail than the other arm thereby to urge said window longitudinally in its plane in one direction or the other during the vertical movement thereof.

8. In a regulator mechanism for a vehicle body window, a rail secured to the lower edge of the window, a pair of oppositely swinging arms having devices at their outer ends slidingly engaging said rail, one of said arms having means cooperable with said rail for shifting the window in its plane into or out of position when fully raised

to provide a ventilating slot at one upright edge of the glass, and said arms having springs of materially different characteristics associated with said devices for effecting a differential pressure of said arms on the rail, the strength of one of said springs being of the order of twice the strength of the other spring.

9. In a vehicle body having a window frame and a sliding glass guided therein, a rail carried by said glass, means for moving said glass in its plane from fully closed position into position to provide a ventilating slot between the forward upright edge of the glass and said frame, means for moving the glass from said ventilating position downwardly in a vertical direction, and differential spring means engaging said rail and effective to urge the glass longitudinally in its plane during its vertical travel.

10. In a vehicle body having a window frame and a sliding glass guided therein, means for moving said glass in its plane from fully closed position into position to provide a ventilating slot between the forward upright edge of the glass and said frame, means for moving the glass from said ventilating position downwardly in a vertical direction, and differential spring means effective to urge the glass longitudinally in its plane during its vertical travel, said second named means including oppositely swinging arms and said differential means including springs adjacent the outer ends of said arms of materially different compression characteristics.

CLARENCE E. RICKEL.
